UNITED STATES PATENT OFFICE

WALTER B. CLIFFORD, OF FRAMINGHAM, MASSACHUSETTS, ASSIGNOR TO THE CLIFFORD CORPORATION, OF BOSTON, MASSACHUSETTS, A CORPORATION OF MASSACHUSETTS

OIL-RECTIFYING APPARATUS FOR INTERNAL-COMBUSTION MOTORS

Application filed February 1, 1926. Serial No. 85,394.

The present invention relates to internal combustion motors and more particularly to apparatus embodied therein for the purpose of removing diluents from the crank case oil during the operation of the motor.

5 The present invention is in many respects an improvement on the apparatus disclosed and claimed in my application filed May 16, 1924, Serial No. 713,857. One object of the 10 present invention is to design apparatus of this type which may be embodied in existing motors without substantial change and which utilizes to the utmost the heat available from the exhaust gases. A further object of the 15 invention is to simplify and improve apparatus of this character in a manner to make it easily accessible for repair or replacement of parts and for the purpose of cleaning the interior in the event that this becomes necessary. 20 A still further object of the invention is to reorganize and improve apparatus of this character in order to make available quantity methods of production and otherwise facilitate the manufacture.

25 With these and other objects in view, the various features of the invention consist in certain novel features of construction, combinations and arrangements of parts herein-after described and claimed, the advantages 30 of which will be obvious to those skilled in the art from the following description.

In the accompanying drawings illustrating the preferred form of the invention,

Fig. 1 represents a section in elevation of 35 the improved form of rectifying apparatus removed from the motor in which it is embodied; and

Fig. 2 is a similar section in elevation taken at right angles to the section shown in Fig. 1.

40 The apparatus shown in the illustrated embodiment of the invention functions in a manner similar to that disclosed in the application hereinbefore referred to. According to this previous application, the oil to be 45 rectified is delivered to the rectifying chamber from the usual lubricating system of the motor, the oil supply line leading from the pressure side of the pump. The delivery of oil into the rectifying chamber is controlled 50 by a thermostatically operated inlet valve

which remains closed or substantially so until the temperature within the chamber is elevated to the distilling range. Thereafter the valve is opened, permitting the entrance of fresh oil under pressure from the 55 pump, and remains open until the temperature within the chamber drops sufficiently to cause closure of the valve. The valve remains closed, preventing further entrance of oil until the temperature is again 60 elevated to the predetermined distilling range, when thereafter the cycle is repeated, the duration of oil flow and the time intervals lapsing therebetween being dependent on the 65 heat of the exhaust, the temperature of the incoming oil and other factors which enter into the amount of heat usefully employed in raising the temperature of oil within the chamber. The oil, after passing through the 70 rectifying chamber and being elevated to the distilling range, is returned to the crank case of the motor in any desired manner. The vapors distilled from the oil, and which may represent either vapors of gasoline, kerosene, or similar fuel or water vapor, are discharged 75 from the rectifying chamber above the liquid level and conducted either into the air intake of the carburetor, discharged directly into the atmosphere, or if so desired led to a condenser for reuse.

80 In the illustrated embodiment of the invention, the rectifying unit is adapted to be connected in the exhaust line in any desired manner.

85 Referring particularly to the drawings, the rectifying unit comprises a casting 10 having an elongated, substantially cylindrical rectifying chamber 12 formed therein and terminating at its upper portion in a relatively shallow, bowl-shaped and outwardly flaring chamber 14. Completely surrounding the cylindrical portion of the rectifying chamber but entirely separated therefrom is a heating chamber 16 in direct communication with the exhaust gases through 90 ports 18 and 20. The ports 18 and 20 are connected into the exhaust line, indicated at 24, through the medium of coupling sleeves 26 threadedly engaging with heads 28 formed 95 on the casting and having inturned portions 100

30 which engage behind annular flanges 32 formed on the exhaust line. The coupling sleeves 36 serve to clamp the flanges of the exhaust line to the heads 28 and form substantially gas-tight joints through the interposed packing 34, as will be evident. The upper portion of the casting 10, and more particularly the bowl-shaped chamber 14, is closed by a head 40 which is connected to the casting through threaded members 42. Positioned centrally of the head is a sleeve 44 which in turn is connected with a relatively thin wall tube 46 which projects downwardly throughout substantially the entire length of the cylindrical chamber 12. The head 40, the sleeve 44 and the tube 46 may be conveniently secured in assembled relation by a welded area, indicated at 48, which rigidly connects the three members together throughout the area of contact. The head 40 may be conveniently drawn or stamped from sheet metal and provided with depressed flanges 50 and 51 for the reception respectively of a plug 54 and a fitting 56 forming a connection for the vapor outlet pipe 58. The sleeve 46 encloses and supports a bellows thermostat 60 which is connected to the sleeve at its lower end through set screws 62 engaging the sleeve and a head 64 forming a part of the thermostat. The upper end of the thermostat carries an inlet valve 66 which is in the form of a hollow sleeve connected to the head 68 through a stem 70. The sleeve valve 66 is guided within a head 72 provided with valve ports 74. The head 72 threadedly engages at 76 with the sleeve 44 and may be rotatively adjusted to vary the position of the ports 74 with relation to the sleeve valve 66. The valve head may be located in adjusted position by a clamp nut 80 engaging with the sleeve 44. It will be evident that as the bellows thermostat 60 expands, due to an increase in temperature within the chamber, the sleeve valve is moved upwardly until the small ports 82 in the upper portion of the valve register with the ports 74 in the head. This upward movement of the valve, due to the expansion of the thermostat, is resisted by a light spring 86 extending within the valve and intended to aid in returning the thermostat and valve to its initial inoperative position. The restoring spring 86 is engaged at its upper end by a cap nut 90 threaded upon the upper end of the head 72, as indicated in Fig. 1. Incoming oil is delivered to the port 74 by a swivel fitting 99 surrounding the upper portion of the head 72 and having a recessed annular chamber 94 which insures a constant supply of oil to the port 74. The chamber 94 is in constant communication with an oil inlet pipe 96 through a passage 98. A liquid-tight connection between the oil inlet pipe 96 and the interior of the fitting 99 is secured by a threaded sleeve 98 surrounding the pipe and having a tapered inner end

100 which grips the pipe in a manner to form a liquid-tight joint as the sleeve is threaded into the fitting in a manner which will be evident to those skilled in the art. Leakage of oil above and below the fitting 74 is prevented by gaskets 102 engaging on opposite sides of the fitting and clamped to the fitting by the cap nut 90. With this construction, when the sleeve valve 66 is elevated sufficiently to cause registration of the ports 82 with the stationary port 74, oil is permitted to flow downwardly through the valve and thence into the interior of the rectifying chamber through the series of ports 104. After emerging from the lower series of ports, oil flows downwardly about the thermostat and within the tube 46, thence outwardly through the large openings 106 formed in the lower portion of the tube 46, thence upwardly, as indicated by the arrows, within the space between the wall of the rectifying chamber and the sleeve 46. The level of oil within the chamber is maintained at substantially the line 108, oil discharging by gravity through the outlet pipe 110. Vapor distilled from the body of oil within the chamber rises from the surface of the oil within the bowl-shaped chamber 14 and passes outwardly through the fitting 56 and the outlet pipe 58. The oil return pipe 110 has a capacity considerably in excess of that necessary for the returning oil stream, and is in direct communication with the crank case or filler pipe above the oil level, so that air is permitted to flow upwardly from the oil return pipe in a direction counter to the direction of flow of the oil stream. This upward stream of air removes any vapor which may be entrained with the oil stream, and passes outwardly from the bowl-shaped chamber 14 and the vapor outlet. This air stream in addition to removing vapors entrained with the oil in the return pipe, tends to disperse and disperse any cloud of vapor which may tend to collect in the chamber 14 above the rectifying chamber. The movement of air and the dispersion of the vapor is expedited by openings 112 formed in the upper portion of the sleeve 46, as indicated in Fig. 1, permitting air to flow freely through the upper portion of this member and about the valve 66. The temperature of the oil within the rectifying chamber may be easily ascertained by removing the plug 54 and inserting a thermometric device within the chamber. The operating temperature within the rectifying chamber may be controlled by loosening the check nut 80 and rotating the valve head 72 to vary the position of the port 74 with relation to the ports 82 in the valve sleeve 66. It will be evident that by adjusting the position of the head 72 vertically with relation to the valve sleeve, the temperature at which the two sets of ports register, and accordingly the temperature at which fresh oil is admitted to the

rectifying chamber, may be varied as desired. Obviously the temperature at which fresh oil is admitted is the temperature within the rectifying chamber.

5 This construction has several distinct and important advantages, both from the standpoint of the manufacture, the standpoint of upkeep and maintenance, and the standpoint of its operation. In the first place it will be evident that the construction as a unit may be embodied in existing types of motors without substantial alteration, the unit as a whole being inserted directly in any existing exhaust line where the full volume or substantially the full volume of exhaust gases will be available. The construction may be readily assembled and adjusted for the proper operating temperature by inserting a thermometric device in the rectifying chamber and adjusting the valve in such a manner that fresh oil is admitted to the chamber when the temperature as indicated by the thermometric device is at the desired distilling point. If for any reason whatsoever it is desired to remove the temperature control, this may be readily accomplished by detaching the head and bodily removing the head with the valve and thermostatic control supported thereby. The valve and thermostat assembly may be thereafter detached from the head by disengaging the set screws 62. When the head is removed from the casting 10 the entire interior of the rectifying chamber is exposed for cleaning or other purposes. During the operation of the device, incoming oil flowing downwardly about the thermostat and thence upwardly in contact with the outer wall of the rectifying chamber serves to maintain the thermostat at a temperature 40 lower than the temperature of distillation. Furthermore the thermostat is insulated from the relatively hot outer wall of the rectifying chamber by the double wall of oil flowing in opposite directions and the intermediate partition formed by the tube 46. At the same time the rectifying chamber throughout substantially its entire length is surrounded by a blanket of hot exhaust gases contained within the heating chamber 10. It will be furthermore evident that a relatively small quantity of oil is contained within the rectifying chamber necessitating a minimum of heat for the elevation of this oil to distilling temperature. The result is to provide 50 a construction in which the temperature of the oil is raised to the distilling point within a short time after the operation of the motor is started, and which at the same time provides a capacity sufficiently adequate to rectify the entire contents of the motor crank case.

What is claimed is:

1. An oil rectifier for internal combustion motors comprising a refining chamber of relatively small cross-section throughout the

major portion of its length and terminating at its upper end in an outwardly flared shallow portion, a heating chamber surrounding the refining chamber, a head closing the upper portion of the refining chamber, a thermostat positioned in the lower portion of the refining chamber, a partition surrounding the thermostat and dividing the chamber into two parts, means operated by the thermostat for controlling the admission of oil to the refining chamber, and oil and vapor outlets in free communication with the chamber at the upper flared portion. 70

2. An oil rectifier for internal combustion motors comprising a refining chamber, means for heating the refining chamber, a thermostat extending lengthwise of the chamber, an oil delivery passage communicating with the chamber having an admission port formed therein, a hollow sleeve valve connected to the thermostat and having a port adapted to register with the admission port to admit oil to the refining chamber upon elevation of the oil within the chamber to a predetermined temperature, and oil and vapor outlets communicating with the upper portion of the chamber. 80

3. An oil rectifier for internal combustion motors comprising a refining chamber, means for heating the refining chamber, a thermostat within the refining chamber, a hollow sleeve valve extending lengthwise of the chamber and connected to the thermostat, the sleeve valve being provided with ports adjacent opposite ends, an oil delivery passage provided with an admission port adapted to register with one of the ports in the sleeve valve on predetermined movement of the valve by the thermostat, and oil and vapor outlets communicating with the chamber. 95

4. An oil rectifier for internal combustion motors comprising a casting provided with a centrally-disposed, elongated, refining chamber terminating in an outwardly flared, bowl-shaped portion, an annular heating chamber formed in the casting and surrounding the refining chamber, a thermostat extending lengthwise of the refining chamber in the lower portion, a tubular wall surrounding the thermostat and dividing the chamber into inner and outer portions, an oil admission valve operated by the thermostat to govern the admission of oil in the upper portion of the chamber, an oil outlet pipe of excessive capacity communicating with the upper bowl-shaped portion of the chamber, and a vapor pipe leading from the upper portion of the chamber. 110

5. An oil rectifier for internal combustion motors comprising a vertically-disposed refining chamber of comparatively small cross-section throughout the major portion of its length, means for heating the chamber, a thermostat disposed within the chamber and extending lengthwise, a hollow sleeve valve 125

connected to the upper end of the thermostat and having upper and lower ports formed therein, an oil admission pipe having a stationary port adapted to register with the upper port of the sleeve valve upon extension of the thermostat to a predetermined point, and means for adjusting the port in the oil admission pipe with respect to the ports in the sleeve valve in order to vary the temperature at which oil is admitted to the refining chamber.

6. An oil rectifier for internal combustion motors comprising a refining chamber, means for heating the chamber, a thermostat located within the chamber, a head, a sleeve adjustably mounted in the head, a hollow valve connected to the thermostat and sliding within the sleeve and having ports formed therein, an oil admission port in the sleeve adapted to register with the port in the valve upon movement of the valve to a predetermined position, and means for adjusting the position of the sleeve with respect to the head to vary the point in the cycle of operations at which the ports register.

7. An oil rectifier for internal combustion motors comprising a vertically-disposed, elongated refining chamber, a bellows thermostat extending lengthwise of the lower portion of the chamber, a head closing the upper portion of the chamber, a sleeve mounted in the head, a valve connected to the thermostat and sliding within the sleeve, a swivel oil connection supported on the upper portion of the sleeve, and means for adjusting the sleeve with respect to the head to vary the point in the expansion of the thermostat at which oil is admitted to the refining chamber.

40 8. An oil rectifier for internal combustion motors comprising a casting provided with a centrally-disposed, refining chamber, an annular heating chamber surrounding the refining chamber, a head detachably connected to the upper portion of the casting and enclosing the refining chamber, an oil outlet connected to the casting and communicating with the upper portion of the chamber, a vapor outlet connected to the head communicating with the upper portion of the chamber, a tubular partition depending from the head extending downwardly into the refining chamber, a bellows thermostat extending lengthwise within the partition, a 45 valve sleeve adjustably connected to the head, and a valve connected to the thermostat and sliding within the sleeve to control the admission of oil to the interior of the chamber.

60 9. An oil rectifier for internal combustion motors comprising an elongated refining chamber, means for heating the chamber, a thermostat extending lengthwise of the chamber in the lower portion thereof, a tubular partition surrounding the thermostat and 65 dividing the chamber into inner and outer

parts, a hollow sleeve valve connected to the thermostat and provided with upper and lower ports, the lower of said ports being located below the upper end of the tubular partition, and a valve passage within which the valve slides having an oil admission port therein adapted to register with the upper port of the valve sleeve upon upward movement of the valve to a predetermined point.

In testimony whereof I have signed my name to this specification.
